UNITED STATES PATENT OFFICE.

ALPHONSE LANCTOT, OF WESTCHESTER, NEW YORK.

ICE CREEPER.

Application filed October 2, 1923. Serial No. 666,205.

To all whom it may concern:

Be it known that I, ALPHONSE LANCTOT, a citizen of the United States, residing in Westchester, in the county of Westchester 5 and State of New York, have invented certain new and useful Improvements in Ice Creepers, of which the following is a specification.

The present invention relates to anti-slipping footwear, and particularly relates to ice creepers, and one object of the invention is to provide an ice creeper having a plurality of friction members, each of which has an ice-engagement face of broad or expanded area and roughened to provide a number of small, sharp projections extending slightly above the surface of the engagement face, which, while efficient on all kinds of ice, are particularly so on thin layers of ice covering street pavements and the like, with which the relatively long sharp points usually employed with ice creepers, fail to engage effectually.

Another object is to provide an ice creeper having resiliently supported friction members conducing to ease of walking upon ice.

Another object is to provide an ice creeper of relatively small size, having uncomplicated parts, cheap to manufacture, and readily and quickly assembled.

I attain these objects, and such other objects as may later appear herein by the invention, one of the possible embodiments of which is described by way of example in the subjoined specification, and shown in the accompanying drawing forming part of the specification, in which—

Figure 1 is a rear elevation of the ice creeper;

Fig. 2 is a plan view as seen from the upper side of the ice creeper;

Fig. 3 is a side view, on a smaller scale than Figs. 1 and 2, showing the ice creeper, attached to a shoe;

Fig. 4 is a bottom view of the ice creeper attached to a shoe; and

Fig. 5 is a sectional view of one of the shells having a friction or ice-engaging member therein, a portion of the supporting or shoe plate, and a portion of a strap showing the manner of securing the strap to the shoe plate.

The device comprises the supporting or shoe plate 10, the attaching straps 11 and

12, the shells 13, the springs 14, and the 55 friction members 15.

The supporting or shoe plate is preferably of steel, and preferably is of the shape shown in the drawing, having a straight rear edge 16, intended to abut against the 60 forward side of the heel of the shoe of the user, a bridge portion 17, extending longitudinally across the plate 10 upon which, on the under side thereof, the shells 13 are mounted, and a forwardly extending bearing portion 18 upon which the forward part of the arch of the shoe of the user rests, the bridge portion 17 and bearing portion 18 being transversely concaved to receive conformably the convex curve of the arch 70 of the shoe. The ends of the bridge portion 17 extend outwardly somewhat beyond the outer sides of the shells 13, and have therein openings 19 in which links 20 are loosely secured, the straps 11 and 12 being 75 movably secured at one of their ends to attachment members 20', thus providing play of the links 20 in the openings 19 and play of the straps on the attaching members 20', and conducing to easy adjustment of 80 the straps. The plate 10 is provided in the bridge portion 17 with the opposed slots 21 for attachment of the shells 13 to the bridge portion as later described.

The shells 13 are hollow cylinders, preferably of steel, each of which has formed on the upper edge thereof the upstanding opposed lugs 22 and has formed on the interior thereof at its bottom the ledge or flange 23, the lugs 22 being receivable in 90 the slots 21 before mentioned for attaching the shells to the bridge portion, the purpose of the ledge or flange 23 being later stated.

The helix springs 14 are received in the interiors of the friction members 15, later 95 described, and are of a diameter to fit loosely in the interiors and permit compression and expansion of the springs therein.

The friction members 15 are hollow cylinders, preferably of hard steel, open at one 100 end and closed at the other end. Each friction member has an enlarged or body portion 24 which is slightly less than the diameter of the interior of a shell 13, whereby the body portion of the friction member 105 fits snugly the interior of the shell for sliding movement of the friction member in the shell, the body portion 24 being engageable

with the flange or ledge 23 of the shell for preventing withdrawal of the friction member from the shell at that end of the shell.

The closed ends 25 of the friction members 15 are of less diameter than the body portion 24 and on their exterior faces are roughened or otherwise arranged to provide a number of sharp projections or sharp ridges, such as 26, extending slightly above the planes of the exterior faces of the closed ends of the friction members and intended to engage with, or bite into, the ice or other smooth surface.

To assemble the parts of the creeper in operative relation, the springs 14 are inserted in the friction members 15, the lower ends of the springs being seated on the interior of the closed ends of the friction members; the friction members are inserted in the shells 13 at the upper ends of the shells, the reduced ends 25 of the friction members extending through the openings at the lower ends of the shells, the lugs 22 being passed through the slots 21 of the bridge portion 17 and turned over on the upper side thereof for securing the shells to the bridge portion, the upper ends of the springs 14 bearing against the under side of the bridge portion 17, the pressure of the springs being downward and tending to force the friction members out of the shells, the tension of the springs being arranged to maintain the reduced ends 25 of the friction members in such projection from the shells as to permit the engagement faces 26 of the friction members to be in a plane sufficiently below the plane of the wear face of the heel of the shoe of the user of the creeper to engage effectually, or bite into, the ice or smooth surface; the straps 11 are buckled over the instep of the shoe of the user and the straps 12 are carried rearwardly and crossed over each other at the back portion of the shoe and carried forwardly and buckled together around the ankle of the user, the links 20 and movable attachment of the straps thereto conducing to ease of adjustment and comfort in use of the creeper, and the resilient support of the friction members conducing to the ease of walking on the ice.

Having thus described my invention, it should be understood that there may be modifications thereof and variations there-

in without departing from the spirit of the invention, or exceeding the scope of the appended claims.

What I claim and desire to protect by Letters Patent is:

1. In a creeper of the character described, the combination with a spring abutment, of a cylindrical shell open at both ends and having at its lower end an annular interior flange, a friction member of cylindrical form, receivable in said shell having a shoulder engaging said annular flange and having a closed end portion, said closed end portion having a plane outer face provided with projections for engaging a smooth surface, and a coil spring receivable in the friction member and cooperating between the friction member and the spring abutment for resiliently maintaining the engagement end of the friction member in projection below the plane of the shell when the shell and friction member are in operative relation. 75

2. In a creeper, the combination of, a shoe plate comprising a bridge portion and a forwardly extending bearing portion and having a straight rear edge; the bridge portion having opposed slots therein and having at each end a link loosely secured thereto; the bridge and bearing portions being transversely concaved; cylindrical shells open at both ends, having on their upper edges upstanding lugs for passing through said slots for securing the shells to the bridge portion and having at their lower ends annular interior flanges; friction members of cylindrical form receivable in said shells, having open ended body portions engaging said annular interior flanges and having reduced closed end portions, said closed end portions having plane outer faces provided with projections for engaging a smooth surface; springs receivable in the friction members and cooperating between the friction members and the under side of the shoe plate for resiliently maintaining the engagement ends of the friction members in projection below the plane of the shells when the shells and friction members are in operative relation; and attachment straps movably attached at one of their ends to said links. 100

ALPHONSE LANCTOT.
